(57) **CLAIM**

We claim the ornamental design for a desk, as shown and described.

DESCRIPTION

FIG. 1 is a perspective view of a desk, showing our new design;

FIG. 2 is an exploded perspective view thereof;

FIG. 3 is a front elevational view thereof;

FIG. 4 is a rear elevational view thereof;

FIG. 5 is a left-side elevational view thereof, the right-side

elevational view being a mirror image thereof;

FIG. 6 is a top plan view thereof; and,

FIG. 7 is a bottom plan view thereof.

The broken lines showing desk legs, computer components and desktop monitors in FIG. 1 depict environmental matter and form no part of the claimed design.

1 Claim, 4 Drawing Sheets
